US00D962222S

(12) **United States Design Patent** (10) **Patent No.:** **US D962,222 S**
(45) **Date of Patent:** **** Aug. 30, 2022**

(54) **LAPTOP COMPUTER**

(71) Applicant: **Quanta Computer Inc.**, Taoyuan (TW)

(72) Inventors: **Chee-Chun Leung**, Taoyuan (TW);
Wen-Hung Tsai, Taoyuan (TW);
Chang-Ta Miao, Taoyuan (TW);
Gwo-Chyuan Chen, Taoyuan (TW);
Chih-Kang Ting, Taoyuan (TW);
Shun-Kai Chuang, Taoyuan (TW)

(73) Assignee: **QUANTA COMPUTER INC.**,
Taoyuan (TW)

(**) Term: **15 Years**

(21) Appl. No.: **29/724,155**

(22) Filed: **Feb. 13, 2020**

(30) **Foreign Application Priority Data**

Oct. 31, 2019 (TW) 108306729

(51) **LOC (13) Cl.** **14-02**

(52) **U.S. Cl.**
